G. N. HEIN

DRIVING SHIELD

Filed Jan. 8, 1923

Patented Apr. 22, 1924.

1,491,399

UNITED STATES PATENT OFFICE.

GEORGE N. HEIN, OF SAN FRANCISCO, CALIFORNIA.

DRIVING SHIELD.

Application filed January 8, 1923. Serial No. 611,476.

To all whom it may concern:

Be it known that I, GEORGE N. HEIN, a citizen of the United States, residing at city and county of San Francisco and State of California, have invented certain new and useful Improvements in Driving Shields, of which the following is a specification.

The present invention relates to a driving shield and particularly to that type of shield 10 illustrated in United States Letters Patent #1,437,656, granted to me Dec. 5, 1922.

The present shield relates to a construction designed particularly to assist a vehicle operator in safely driving a vehicle by reducing during day driving the direct glare of the sun or its reflection from the street or projecting parts of the vehicle, and during night driving, by eliminating the glare from the headlights of an approaching vehicle or 20 the reflection from roadlights or wet pavements. A further object of this invention is to provide a shield carried by a universally movable bracket and which shield mounts pivoted members or shutters adapted to swing to provide a pocket in advance of 25 or in rear of the shield sight opening afforded.

The present invention consists particularly in a frame mounting at one side, a pair of 30 pivoted shutters independently movable and at its other side a pivoted plate and mounting between said shutters and plate a vertically movable translucent member adapted for dropping below the lower edge of the 35 frame and having an unbound or free lower edge, the pivoted plate lying in spaced relation below a fixed plate affording a normal driving opening through the frame.

With the above mentioned and other objects in view, the invention consists in the novel construction and combination of parts hereinafter described, illustrated in the accompanying drawings, and set forth in the claims hereto appended, it being understood 45 that various changes in the form, proportion, size and minor details of construction within the scope of the claims may be resorted to without departing from the spirit or sacrificing any of the advantages of the 50 invention.

To more clearly comprehend the invention, reference is directed to the accompanying drawings, wherein:

Fig. 1 is a view in longitudinal section of 55 one form of universal adjustable mounting illustrating the shield in side elevation, at

the outer end thereof disclosing the shutters and pivoted plate together with the translucent member in various positions.

Fig. 2 is a fragmentary top plan view of 60 the universal extension bracket support.

Fig. 3 is a cross sectional view taken on the line 3—3 of Fig. 1.

Fig. 4 is a view in elevation of the shield viewed from the face mounting the fixed and 65 pivoted plates, and illustrating the translucent member in a position dropped below the lower frame edge.

Fig. 5 is a vertical sectional view taken on the line 5—5, Fig. 4, but with the shutters removed from the frame.

Fig. 6 is a view in detail of the grooved recess for receiving the end bracket and

Fig. 7 is a perspective view of the shield illustrating the pivoted plate and the upper 75 and lower shutters of the pair in angular position and further illustrating the translucent member in its raised position.

Referring more particularly to the several views of the drawings wherein like characters of reference designate corresponding parts, 1 indicates a support of either the top or side frame member of a vehicle windshield. To this is secured by clamp screws 2 a U-shaped clamp 3 mounting a tapered stud 4 which is received within the tapered opening 5 of a connecting member 6, the movement of the member 6 about the stud 4 being controlled by the adjustment of the nut 7 thereon. The member 6 is connected by a 80 fastener 8 disposed at right angles to the stud 4 with the inner end of an extensible support 9. This support comprises the telescoping tubular members 10 and 11, the member 11 being longitudinally slotted as at 85 12 to receive the head of a guide screw 13, the latter member retaining a spring 14 in the slit inner end 15 of the telescopic member 10, creating a friction to retain the member 10 in its adjusted position within the 90 member 11. The outer end of the member 10 is annularly grooved as at 16 between shoulders 17 and within said groove is received the upper curved ends 18 of an end bracket, the bracket consisting of duplicate 105 members 19 held together by a tension screw 20. The lower ends of the members 19 are apertured as at 21 to receive between them the spherical end 22 extending upwardly from the center of the upper member of the 110 shield frame. While this type of universally adjustable extension bracket is illustrated

and described it is to be understood that any form of adjustable bracket may be employed in connection with the present shield. The shield comprises a rectangular open frame 23 and within the channeled side frame members 24 of which is mounted for vertical adjustment a translucent member or glass 25 preferably of amber or amethyst color. The translucent or glare modifying member is reinforced on its ends by the members 26 which have frictional contact with channels of the frame 24 and retain the glass in its adjusted position within the frame. The channeled side members 24 of the frame are connected at their upper ends by a top cross bar 27 and to one face of the said channeled side members is secured the opposite ends of the fixed plate 28, the lower edge of which extends approximately one-third the distance downwardly from the top or upper end of the channeled side frame members 24. The fixed plate 28 in its center is vertically slotted as at 29 to provide a channel or glide for receiving the operating button 30 carried centrally of the upper edge of the translucent member 25. Associated with the same side of the frame as is the fixed plate and cooperating with the lower edge of the frame is a plate 31 pivoted or hinged as at 31' and adapted for swinging in an arc of 180° from the position illustrated in full lines, Fig. 1 to the position illustrated in dotted lines of the same figure, the latter position placing the plate below the lower ends of the channel side frame members 24. When the plate is in its normal full line position, Fig. 4, there is afforded between its upper edge A and the lower edge B of the fixed plate 28 what may be termed a normal sight or driving opening C. When the plate 31 is in its normal position and the translucent member 25 is lowered, the upper edge of the plate forms a stop or limit for the member 30 carried by the member 25. The plate 31 at its ends adjacent its upper ends carries the spring retaining flanges 32 adapted to engage the outer faces of the channeled side frame members 24. To the upper and lower edges of the opposite face of the frame from the plate 28 are hinged as at 33 and 34 the respective upper and lower shutters 35 and 36, both coextensive with the width of the frame and the upper shutter being of a length when lowered to close the normal driving opening C. The lower shutter is of a length when raised to close approximately the lower half of the normal driving opening C for its full width. The shutters are adapted for pivotal movement and said shutters are adapted to be retained in their angular adjusted position by the tension or adjustment of the nuts 38 carried on the ends of the hinge pintles 39.

Through the medium of the spherical member 22 it will be understood that either face of the frame 24 may be positioned toward the vehicle operator.

The device being constructed as in the drawing, some of its adjustments may be briefly described as follows.

With the shield in closed position, that is, with the shutters 35 and 36 disposed in overlapped relation flat with one face of the shield and the shield tilted outwardly in the direction of the angle of the upper shutter 35 of the pair as illustrated in Fig. 1, the shield may be used as a visor to shut out overhead lights and all approaching headlights enabling the driver to have road vision beneath the lower edge of the shield. When in this position the translucent member may be dropped below the lower edge of the frame affording the driver a modifying glass through which the headlights of approaching vehicles may be viewed if it is desirable and at the same time overcoming all glare.

With the shutters 35 and 36 outwardly disposed and the shield adjusted to a substantially vertical position in the desired proximity to the eye of the driver, the opening of the shutters 35 and 36 will afford through the normal driving opening C a driving opening the view through which may be modified by the raising of the glass 25. The adjustment of the shutters renders the unobstructed vision variable and enables the desired degree or amount of reflection from the street or direct rays from above striking the eye of the operator to be controlled. This driving opening may also be varied by moving the shield to and from the eyes of the operator or by inclining the same forwardly or rearwardly from its vertical position.

The opening of the shutters affording the driving opening through the shield protects the glass from the reflection glare and enables the operator to readily see therethrough, this being accomplished by the formation of the pocket in advance of the frame. When a driving opening larger than the normal driving opening is desired through the shield, the same can be obtained by opening the shutters 35 and 36 and lowering the pivoted plate 31 at which time the glass 25 may be raised or lowered to modify the driving opening or to provide such unobstructed driving opening clearance as may be desired, the remaining driving opening being modified by the operator being required to view the road and approaching vehicles through the member 25.

I claim:

1. A driving shield comprising an open frame, a shutter hinged at one edge to one longitudinal side edge thereof and adjustable angularly from the face of the frame,

a member adjustably mounted within the frame to vary the clear vision opening there-through, and means for mounting the shield to permit its universal adjustment relative 5 to its support.

2. A driving shield comprising a frame, a pair of non-transparent shutters carried by the frame, said shutters adapted for independent angular adjustment outwardly 10 from one face of the frame for varying the vision opening through the frame between the free edges thereof.

3. A driving shield comprising an open frame, a pair of opaque shutters carried by 15 the frame, said shutters adapted for independent angular adjustment outwardly from one face of the frame for varying the vision opening between the free edges thereof, a translucent member vertically adjustable 20 within the frame and having an unobstructed lower edge, said member adapted for adjustment within the frame to project its lower edge below the frame, and means for mounting the shield to permit its universal adjustment relative to its support.

4. A driving shield, comprising an open frame, a pair of non-transparent members hinged respectively to the upper and lower edges thereof, said members capable of 30 folding to close the frame opening and of independent angular adjustment outwardly from one face of the frame to afford a variable transparent sight opening between their free edges, and means for mounting the 35 shield and a translucent member carried by the frame and movable therein within the

sight opening afforded between the free edges of the members.

5. A driving shield comprising an open frame, a pair of non-transparent members 40 hinged respectively to the upper and lower edges thereof at opposite faces of the frame, said members capable of independent angular adjustment outwardly from their respective frame faces to afford a variable vision 45 opening through the frame between their free edges, and means for mounting said shield to permit its universal adjustment relative to its support.

6. A driving shield comprising an open 50 frame, a pair of members hinged respectively to the upper and lower edges thereof at opposite faces of the frame, said members capable of independent angular adjustment outwardly from their respective frame faces 55 to afford a variable vision opening through the frame between their free edges, a transparent member carried by the frame and movable into said vision opening, and means for mounting said shield to permit its universal adjustment relative to its support.

7. A driving shield comprising a frame, a pair of shutters associated with the frame, said shutters adapted for independently angular adjustment outwardly from one face 65 of the frame for varying the vision opening between the free edges thereof, and a non-transparent member vertically adjustable within the frame.

In testimony whereof I have signed my 70 name to this specification.

GEORGE N. HEIN.
